UNITED STATES PATENT OFFICE

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 18,163, dated March 6, 1888.

Application filed February 9, 1888. Serial No. 263,529. Term of patent 14 years.

To all whom it may concern:

Be it known that I, HERMAN IHLENBURG, (assignor to the MACKELLAR, SMITHS & JORDAN COMPANY,) of the city and county of 5 Philadelphia, Pennsylvania, have invented and produced a new and original Design for a Font of Printing-Type, of which the following is a specification.

The nature of my design is clearly shown 10 in the accompanying typographic impression, to which reference is made; and it consists of an unshaded letter having the triangular terminations at top and bottom, as shown, of the up-and-down portions.

15 The faces of the A, B, and H are ornamented by the light inclined lines. The central ornaments of the E and F consist of the inclined line gradually widened upon the right hand and crossed by an inclined line extending 20 above and below the widened portions, and forming a triangle. The rounding portion of the P and R is narrowed upon the left hand a short distance before it meets the up-and-down portion of the letter. The tail of the Q is 25 gradually widened into a triangular termination at its base. The character of the design is preserved in the lower-case and numerals.

Having described my invention, I claim as new—

The design for a font of printing-type, as 30 shown and described, the same consisting of an unshaded letter having the triangular terminations at top and bottom of the up-and-down portions, the faces of the A, B, and H ornamented by the light inclined line, the 35 central ornaments of the E and F consisting of the inclined line gradually widened upon the right hand and crossed by an inclined line extending above and below the widened portion and forming a triangle, the rounding portion of the P and R narrowed upon the left hand a short distance before it meets the up-and-down portion of the letter, the tail of the Q gradually widened into a triangular termination at its base, and the character of the design 40 preserved in the lower-case and the numerals. 45

HERMAN IHLENBURG.

In presence of—

C. F. HUCH,
HERMAN METIUS.
